UNITED STATES PATENT OFFICE.

ALLAN C. NELSON, OF FLUSHING, NEW YORK.

BALL GAME.

971,626.

Specification of Letters Patent.

Patented Oct. 4, 1910.

Application filed January 20, 1910. Serial No. 539,030.

To all whom it may concern:

Be it known that I, ALLAN C. NELSON, a citizen of the United States, and a resident of Flushing, Long Island, New York, have 5 invented certain new and useful Improvements in Ball Games, of which the following is a specification accompanied by drawings.

This invention relates to ball games, and 10 more particularly to a ball game in which a ball is projected against a target or targets, thereby causing a playing object to be projected through the air.

The objects of the invention are to secure 15 a simple and cheap device combining both the features of chance and skill, whereby playing objects are projected through the air from a frame, by means of rocking devices operated by a ball rolled against said 20 devices. To these ends the invention in one of its preferred forms is described and claimed in this specification and shown in the accompanying drawings in which—

Figure 1 is a perspective plan view of devices embodying the game, Fig. 2 is a longitudinal section of the frame, and Fig. 3 is a detail perspective view of one of the rocking levers.

Referring to the drawings, A represents a 30 frame of any suitable construction, open at the front beneath the front cross bar B, to enable a ball C to be rolled thereunder. On the frame are mounted one or more pivoted levers D of any suitable form, preferably 35 made out of wire. These levers as shown are of bell-crank form, having depending portions E forming targets and rearwardly extending carrying portions F forming supports for playing objects such as the balls 40 G. The bell-crank levers are preferably pivoted on the transverse rod H, and a support J extends beneath the arms F. A retaining piece P may extend across the frame A at the bottom to hold the balls C as they 45 enter the box. If desired targets K of suitable material as tin may be fastened to the depending portions E of the rocking levers. A playing target L may if desired be arranged at a suitable distance in front of the 50 frame or box A.

In playing the game, the ball or balls C are rolled against the targets K and thereby one of the rocking levers D is rocked, thus projecting a playing object G forwardly

through the air in the direction of the large 55 target L. The number of points counted depends upon the division in which the playing object strikes. It will be seen that the rocking levers D are slideable along the rod H, so that their distance apart may be 60 adjusted to suit the players. If desired scrap baskets may be placed on the floor instead of the target L or else the players 65 may catch the balls as they are projected out of the box. Obviously the game may be played either in-doors or out-doors as desired.

I claim and desire to obtain by Letters Patent the following:—

1. A ball game comprising in combination 70 a frame, pivoted rocking levers mounted thereon and provided with carrying portions adapted to support playing objects, and a ball adapted to be projected against said rocking levers and thereby project said 75 playing objects forwardly.

2. A ball game comprising in combination a frame, a pivoted bell-crank lever mounted thereon, one leg of which extends downwardly to form a target and the other leg 80 extending rearwardly to form a carrying portion for a playing object, and a ball adapted to be projected against said target.

3. A ball game comprising in combination a frame, pivoted levers mounted on said 85 frame and having depending portions adapted to be struck by a ball and substantially horizontally lying carrying portions adapted to support playing objects, and a ball adapted to be projected against the depending portions of said levers.

4. A ball game comprising in combination a frame, pivoted levers mounted thereon, each lever consisting of downwardly depending portions forming targets, and carrying portions adapted to normally lie substantially horizontally and having means for supporting playing objects, and a ball adapted to be projected against the depending portions of said levers.

In testimony whereof I have signed this specification in the presence of two subscribing witnesses.

ALLAN C. NELSON.
